CLAIM

I claim the ornamental design for a bed frame leg, as shown and described.

DESCRIPTION

FIG. 1 is a front perspective view of a bed frame leg showing my new design;

FIG. 2 is a front side view thereof;

FIG. 3 is a rear side view thereof;

FIG. 4 is a right side view thereof;

FIG. 5 is a left side view thereof;

FIG. 6 is a top plan view thereof; and,

FIG. 7 is a bottom plan view thereof.

1 Claim, 6 Drawing Sheets
